F. TINKER

PRODUCTION OF PETROL

Filed March 28, 1922

Inventor
F. Tinker,
By Marks & Clark
Atty's

UNITED STATES PATENT OFFICE.

FRANK TINKER, OF ERDINGTON, BIRMINGHAM, ENGLAND.

PRODUCTION OF PETROL.

Application filed March 28, 1922. Serial No. 547,474.

To all whom it may concern:

Be it known that I, FRANK TINKER, a subject of the King of Great Britain, residing at Erdington, in the city of Birmingham, England, have invented certain new and useful Improvements Relating to the Production of Petrol, of which the following is a specification.

In the specification of a former United States Letters Patent No. 1,393,184, granted to me, I have described a process for the production of petrol (or gasoline) from crude mineral oils by means comprising a still, a superheating or cracking chamber, and a fractionating column. In the said process superheated vapour from the cracking chamber was mixed with a stream of crude oil, and the mixture was delivered to the fractionating column, and the whole of the residue collecting at the base of the fractionating column was returned to the still for partial conversion into superheated vapour.

When dealing with some crude oils, particularly those containing asphaltic compounds and sulphur, I find it undesirable to return to the still the whole of the residue after treatment of the crude oil with superheated vapour, and the object of this invention is to enable the heavier constituents, which ordinarily contain impurities, to be removed from the system before fractionation.

According to the present invention pre-heated crude oil is mixed with superheated oil vapour in a mixing chamber; the intermingled products are then passed to a separating chamber where the heavy residues are collected and removed, the vapours passing on to a fractionating column; condensate from the lower part of this column is withdrawn to the still and superheater for production of the superheated vapour required for admixture with the crude oil, and the uncondensed vapour is passed on to a condenser.

The accompanying drawing illustrates diagrammatically one mode of carrying the invention into effect.

Referring to the diagram, I employ in combination a still *a*, a superheater or cracking chamber *b*, a mixing chamber *c*, and a fractionating column *d*. A separating chamber *e* is arranged between the mixing chamber and the fractionating column. The superheated vapour and crude oil are brought together at the upper end of the

mixing chamber *c*, and the lower end of the separating chamber *e* is provided with a pipe *j* by which residue collecting in the said chamber can be drained continuously from the system. The various parts are connected by pipes as shown.

For preheating the crude oil I may employ a variety of methods. Thus e. g. the residue from the chamber *e* may be passed through one compartment of the heat interchanger *f* for imparting its heat to the crude oil. Under the action of a pump *g* the crude oil is forced through the other compartment of the heat interchanger *f*, to a fire-heated pipe *h* where its temperature is further raised. Both these heating devices may be supplemented by others in which the heat of vapours delivered by the system is utilized. Any of these methods may be used singly or in combination. I find in practice that preheating by heat obtained from the residue, and subsequent heating by fire is convenient.

In the preheating operation the crude oil delivered into *c* is raised to such a temperature that the heat of the superheated vapour from *b* can be used for evaporating the lighter and medium fractions from the crude oil. A greater volume of distillate is thus taken from the crude oil than would be obtained if all the heating were effected by the superheated vapour, and distillates only pass on from the mixing chamber *c* and the chamber *e* to the fractionating column *d*. In the latter the vapours are fractionally condensed in such a way as to return to the still *a* sufficient oil to provide the required superheated vapour. As above stated the heavy residues are drawn out of the system at the part *e* and condensates only are collected in *d*. Vapours not collected in *d* pass to a condenser *i* and after condensation are withdrawn.

I claim:

1. In the production of low boiling point hydrocarbons from high boiling point hydrocarbons, the process comprising mixing superheated hydrocarbon vapors with a main stream of preheated crude hydrocarbon in a mixing chamber, passing the mixture in a restricted stream through a pipe to an enlarged drum, drawing off a part, at least, of the condensate from said drum and passing the vapors into a fractionating column, delivering the condensate from the fractionating column into a still, generating

vapors in the still and superheating the still vapors in the superheating device for subsequent mixture with the main stream of preheated crude hydrocarbon in a continuous process.

2. In the production of low boiling point hydrocarbons from high boiling point hydrocarbons, the process which consists in mixing superheated hydrocarbon vapors with a main stream of preheated crude hydrocarbons in a mixing chamber, passing the mixture in a restricted stream through a pipe to an enlarged drum, drawing, at least, a part of the condensate from said

drum and passing it through a heat exchanger to preheat the stream of crude hydrocarbons, passing the vapors from the separating drum into a fractionating column and delivering the condensate from the latter into a still, generating vapors in the still, and superheating the still vapors in the superheating device for subsequent mixture with the main stream of preheated crude hydrocarbons in a continuous process.

In testimony whereof I have signed my name to this specification.

FRANK TINKER.
